DISPLAY STAND

Leon H. Best, Galva, Ill., assignor to John H. Best & Sons, Inc., Galva, Ill., a corporation of Illinois

Application October 20, 1937, Serial No. 169,963

4 Claims. (Cl. 211—45)

This invention relates to display racks for holding a number of carpet or rug samples and the like so that the individual samples can be quickly and easily shown to a customer.

- 5 In displaying sheet samples it has been customary to stack them one upon the other in piles on the floor or on stands, or suspend them from suitable racks supported on the walls of the display room. When the sheet samples are placed 10 in piles an untidy pile results as the salesman removes the various sheets from the pile and replaces them during the course of the business day. When sheet samples are suspended from wall racks it is difficult for many customers to 15 visualize the appearance of the sample in the manner in which a customer desires to use the product. This is especially true of carpets, rugs and other floor coverings. It is, therefore, highly desirable to display the samples in such a manner 20 that the customer can obtain a substantially accurate impression of how the rug or carpet will appear on the floor in his home or business establishment.

The most satisfactory method of making such 25 a display is by the use of display stands which securely hold the samples in substantially horizontal position close to the floor. Various devices have been used whereby the samples are secured to the stand so that the topmost samples may be 30 thrown back to disclose the view of the samples which the salesman intends to display to the customer.

For various reasons such as for obtaining different light conditions it may be desirable to 35 remove the particular sample from the middle of the pile and take it to a different part of the display room. The salesman desires to effect such a removal with as little confusion as possible and with the clamping devices heretofore used 40 on display stands this has been difficult, if not impossible.

It is, therefore, the primary object of this invention to store samples on a display rack in such 45 a manner that they may be readily removed therefrom without confusion and general disarrangement of the remaining samples.

It is another object to effect such a removal in as short a time as possible so that the customer's attention does not have a chance to be 50 diverted.

It is a further object of the invention to enable the placement of additional samples on a display rack in a speedy manner so that the 55 rack and the samples thereon will not be unavail-

able to the salesman for display purposes for a prolonged period.

A still further object of the invention is to provide a display rack which is operable in a quick and efficient manner to secure samples of sheet material such as rugs, carpets and the like secured thereon by clamping means which are substantially concealed from the view of the customer, whereby his attention to the samples being displayed is not diverted by the clamping apparatus.

In the accompanying drawing wherein a preferred embodiment of my invention is illustrated,

Fig. 1 is a perspective view of the display rack showing a plurality of samples clamped thereon for display;

Fig. 2 is a sectional view taken on line 2—2 of Fig. 1;

Fig. 3 is a sectional view taken on line 3—3 of Fig. 2; and

Fig. 4 is a sectional view taken on line 4—4 of Fig. 3.

Referring to the drawing, the bed 5 is supported in a slightly angular relation to the floor by means of relatively short legs 6 at the front thereof and by relatively long legs 7 at the rear. The rear legs 7 are secured by means of a set screw 7' in the throat 8 of the clamping bracket 9. The clamping bracket is provided with a pair of oppositely disposed flanges 10, 11 which are secured to the rail 12 of the frame of the stand by means of screws 13. The bracket 9 is provided with a clamp chamber 14 which extends from the rear to the front thereof and is open at the rear. An opening 15 is provided at the top of the chamber and another opening 16 provided at the bottom of the chamber. The opening 16 is in alignment with the throat 8 and the opening 15 is in alignment with the opening 16. Another opening 17 is provided through the portion of the bed 20 which extends beyond the rail and is in alignment with the openings 15 and 16 and the throat 8.

A clamping rod 18 is insertable through the openings 17, 15 and 16 and extends into the hollow leg 7. The rod 18 is provided with a suitable operating knob 19 at its top.

A clamping lever 20 extends into the chamber 14 with its inner end engaged in a recess 21 provided at the rear of the chamber. An opening 22 is arranged through the lever substantially at the point where the lever extends out of the chamber and a pin 23 extends through the opening 22 and is secured at the top and bottom, respectively, of the bracket. The pin 23 is curved 55

on a radius substantially equal to the distance of the opening 22 to the recess 21. A coil spring 24 is arranged about the pin 23 below the lever 20 to normally urge the outer end of the lever upwardly about the inner end of the lever which is fulcrumed in the recess 21. The lever is also provided with an opening 25 between the opening 22 and the inner end thereof. The opening 25 is slightly larger than the diameter of the rod 18 which is adapted to extend therethrough.

A clamping bar 26 is adapted to be arranged across the top of a pile of samples of rugs, carpets or the like 27 and is provided with openings at the ends thereof to receive the clamping rods 18 arranged on opposite sides of the display stand.

In using my invention a pile of rugs 27 is first placed upon the bed 5 and the clamping bar 26 is arranged in place across one end thereof, whereupon the clamping rods 18 are inserted through the openings at the ends of the clamping bar and through the openings 17, 15, 25, 16 and into the hollow legs 7 in succession. In passing through the openings 25 the rod 18 pushes the lever 20 downwardly against the action of the spring 24 which normally urges the outer end of the lever 20 upwardly. The knobs 19 are pressed downwardly by the operator to securely clamp the samples in place. The rod 18 is held in this pushed downwardly position by the frictional engagement of the one side of the opening 25 against the rod 18 by reason of the lever being pushed upwardly by the spring 24 to dispose the lever angularly with respect to the rod 18.

While I have shown and described my invention in a selected embodiment I wish it to be understood that I reserve the right to make all such changes in the form, construction and arrangement of the parts thereof as may fall within the scope of the following claims.

40 I claim:

1. In a display stand having a bed adapted to receive samples of rugs, carpets, and the like to be displayed, a clamping bracket secured in fixed relation with said bed, a clamping bar arranged across the samples to be displayed on said bed, a clamping rod engageable with said bar, a lever pivotally mounted in said bracket and extending therefrom beyond an edge of said bed, said bar, bracket, and lever having aligned openings therethrough to receive said rod, and operating means adapted to frictionally engage said lever with the rod to lock the rod in the aligned openings and selectively operable to release the rod.

2. In a display stand having a frame, a bed mounted on the frame and extending beyond the sides thereof and adapted to receive samples of rugs, carpets, and the like to be displayed, a clamping bracket secured to said frame beneath said bed and arranged between the frame and an edge of the bed, a clamping bar arranged across the samples to be displayed on said bed, a clamping rod engageable with said bar, a lever pivotally mounted in said bracket, said bar, bracket, and lever having aligned openings therethrough to receive said rod, and a hollow leg for said stand secured at its top in said bracket in substantial alignment with the aligned openings and adapted to receive the end of the rod extending through said aligned openings, said lever

being operable to selectively secure the rod in the aligned openings and in the hollow leg.

3. In a display stand having a bed adapted to receive samples of rugs, carpets, and the like to be displayed, a rail secured to said bed therebeneath and arranged inwardly from the side of said bed, a clamping bracket secured to said rail and arranged between the rail and the side of the bed, said bed having an opening therethrough above said bracket, said bracket having a chamber therein open at the rear and having aligned openings at the top and bottom aligned with the opening in the bed and communicating with said chamber, the front wall of the bracket having a recess therein on the chamber side, a clamping lever fulcrumed at one end in said recess and extending outwardly through the opening at the rear of the chamber, said lever having an opening therethrough in substantial alignment with said aligned openings and another opening therethrough between said first-named lever opening and the free end of the said lever, a pin traversing said chamber and secured at its ends in the top and bottom respectively of the bracket and extending through said other opening in the lever, whereby the lever is held in operable position in the chamber, spring means arranged about the pin between the lever and bottom of the chamber and normally urging said lever upwardly, a hollow leg for said stand secured at its top in said bracket in substantial alignment with the aligned openings, a clamping rod extending through the aligned openings and into said leg, said rod having an operating knob at its outer end, and a clamping bar arranged across an end of the sample to be displayed on said bed and having an end thereof arranged beneath said knob for engagement by the knob whereby pressure exerted thereon will automatically clamp the lever upon the rod by action of the spring means upon the lever to secure the samples upon the bed and whereby selective operation of the lever about its fulcrum releases the rod from the lever to permit withdrawal of the rod to release the samples.

4. In a display stand having a bed adapted to receive samples of rugs, carpets, and the like to be displayed, a rail secured to said bed therebeneath and arranged inwardly from the side of said bed, a clamping bracket secured to said rail and arranged between the rail and the side of the bed, said bed having an opening therethrough above said bracket, said bracket having a chamber therein open at the rear and having aligned openings at the top and bottom aligned with the opening in the bed and communicating with said chamber, the front wall of the bracket having a recess therein on the chamber side, a clamping lever fulcrumed at one end in said recess and extending outwardly through the opening at the rear of the chamber, a clamping rod extending through the aligned openings, and a clamping bar arranged across an end of the samples to be displayed on said bed and engageable by said rod whereby said rod is selectively engageable by said lever to secure said bar in clamping relation with said samples.
